Patented Sept. 26, 1916.

UNITED STATES PATENT OFFICE.

GIULIO BACOLINI, OF NEW YORK, N. Y.

SURGICAL INSTRUMENT.

1,199,653.

Specification of Letters Patent. Patented Sept. 26, 1916.

Application filed May 10, 1916. Serial No. 96,575.

To all whom it may concern:

Be it known that I, GIULIO BACOLINI, a subject of the King of Italy, and a resident of the city of New York, borough of Brooklyn, in the county of Kings and State of New York, have invented a new and Improved Surgical Instrument, of which the following is a full, clear, and exact description.

10 My invention relates to surgical instruments particularly adaptable for manipulating the clips applied to incisions.

The object thereof is to provide an instrument which will automatically feed the 15 clips to the plying ends of the instrument after each manipulation of said plying ends.

With the above and other objects in view, the nature of which will more fully appear as the description proceeds, the invention 20 consists in the novel construction, combination and arrangement of parts as herein fully described, illustrated and claimed.

In the accompanying drawings, forming 25 part of the application, similar characters of reference indicate corresponding parts in all the views.

Figure 1 is a top plan view of my instrument; Fig. 2 is a longitudinal section on line 2—2, Fig. 1; Fig. 3 is a bottom-side-up plan 30 view of the instrument; Fig. 4 is a plan view of the clip carrier and feeder in position before it is placed into the instrument support; Fig. 5 is a transverse section on line 5—5, Fig. 1; Fig. 6 is a similar view showing the 35 plier ends forced against the clip; and Fig. 7 is a perspective view of the clip used in connection with the instrument.

Referring to the drawings, 8 is a longitudinal channeled member the longitudinal 40 edges of which are turned inwardly to form flanges 9 which prevent the dropping away of a slide 10 provided within the channeled member 8. The slide is introduced into the channeled member through the rear end 45 thereof. A block 11 plugs the rear end of the member 8. The block is locked to the member by a set screw 12. The block carries a pair of parallelly-spaced rods 13 which extend through the entire length of 50 the member 8. The distance between said rods is equal to the distance between the eyelets of the clip 14; and the distance between the flanges 9 to the bottom of the channeled member 8 is sufficient to easily 55 accommodate prongs 15 at the eyelets of the

clips. The slide 10 has openings through which the rods 13 pass.

A coil spring 16 is provided on each rod between the slide and the block 11, said spring normally forcing the slide away from the block 11 toward the forward end of the member 8. The clips 14 carried by the rod in front of the slide will be fed by the slide toward the forward end of the member 8. At the forward end the member 8 is provided with a lip 17 rising above the bottom and forming an abutment for the clips. The sides of the member 8 at the lip are cut away to clear the way for the clipping ends 18 of the clamping tool 19 mounted on the upper 70 surface of the member 8. The handles of the tool are engaged by a spring 20 which normally maintains the slipping ends apart or clear of the ends of the clip abutting against the lip 17, the spreading of the 75 clipping ends being limited by pins 21 provided on the member 8 (see Fig. 1).

The bottom of the member 8 at the forward end is partly cut out, as shown at 22, to expose the clip abutting against the lip 80 and to permit said clip to bulge therethrough when the same is clamped by the clipping ends of the clamping tool (see Fig. 6). The ends of the rods 13 clear the lip 17 through a distance more than the width of a clip, as 85 best shown in Fig. 3. The sides and the flanges 9 of the member 8 are rounded near the forward end of the tool, as shown best in Figs. 2 and 3, to facilitate the engagement of the clips with the incision to be 90 mended thereby. It will be noted that every time a clip is collapsed by the clamping tool 19 the springs 16 will feed the clips toward the lip 17, the collapsed clip being free to pass into the cut-out of the lip forming an extension of the cut-out 22 in the bottom. The feed of the clips and the clip ends is, therefore, automatic and follows the 95 operation of the clamping tool.

To feed the clips on the rods 13 it is necessary to remove the block 11. To prevent the spring from forcing the slide 10 off the rods, said slide is provided with a hooked extension 23 directed toward the block. The block in turn has a depressible hooked extension 24 extending toward the slide and co-operating with the hooked extension 23. The slide 10 has a milled head 25 above the flanges 9 for bringing the hooked extension 23 into engagement with the hooked exten- 110

- 2
- sion 24 of the block 11. The engagement of the two hooked extensions prevent the springs 16 from forcing the slide toward the ends of the rod. By removing the set screw 12 the block 11 may be removed from the member 8 and therewith the slide 11 which is locked to the block. Clips can then be fed on to the rods 13 against the slide 9 thereupon. See Fig. 4.
- 10 When the rods above the slide are covered by the clips, the rods with the clips are entered through the rear end of the member 8 and the block 11 is locked in position by the screw 12. To release the slide and allow 15 the springs 16 to bring the clips 14 against the lip 17, the depressible hooked end 24 must be depressed; and for that purpose the hooked extension 24 is provided with a projection 26 rising above the flanges. When 20 the hooked end is depressed the hooked extension 24 disengages from the hooked extension 23 and the spring 16 will force the slide toward the forward end of the tool, bringing the clips against the lip 17.
- 25 The member 8, which constitutes the support of the clamping tool and the clip feed, also serves as a holder of the instrument, particularly the portion thereof beyond the handle of the clamping tool which are retained by the smaller fingers of the hand in the manipulation of the instrument. The block 11, rods 13, springs 16, slide 9 and the hooked extension of the slide and the block 30 constitute an automatic feed of the instrument and also the clip carrier.
- 35 While I have described the principle of operation, together with the device which I now consider to be the best embodiment thereof, I desire to have it understood that 40 the device shown is merely illustrative and that such changes may be made as are within the scope of the appended claims.
- I claim:
1. In a surgical instrument of the class 45 described, a channeled support presenting a lip at one end thereof, a block locked to the other end of the support, parallelly-spaced rods extending from the block to the lip and terminating in close proximity to the 50 lip, a slide within the support engaging the rods, springs on the rods between the block and the slide, said spring normally tending to move the slide toward the lip, the portion of the rods lying between the lips and the 55 slides being adapted to carry clips, a clamp on said support having ends for plying clips at the lip, said channeled support being cut out in the bottom at the lip to allow the clips to buckle when collapsed by the clamp, and means for securing the slide to the block 60 whereby the springs on the rods are prevented from forcing the slide away from the block.
2. In a surgical instrument of the class described, a channeled support presenting a lip at one end thereof, a block locked to the other end of the support, parallelly-spaced rods extending from the block to the lip and terminating in close proximity to said lip, clips having eyelets adapted to be 65 threaded on said rods, a slide engaging said rods, springs on said rods normally tending to move the slide away from the block whereby the clips threaded on the rods are moved by the slide toward the lip, said lip 70 forming an abutment for the adjacent clip, a clamping tool secured to the support, said clamping tool having plying ends, said channeled support having the sides thereof cut away at the lips to clear the path for the 75 plying ends of the clamping tool whereby a clip at the lip may be collapsed, said channeled support having a portion of its bottom at the lip cut out to allow the clip collapsed by the plying ends of the tool to buckle therethrough, and means for locking the 80 slide to the block, substantially as and for the purpose set forth.
3. In combination with clips having eyelets at the ends thereof, a pair of spaced rods adapted to be threaded through the eyelets of the clips, a support adapted to accommodate said rods, a slide carried by the rods, springs on said rods engaging the slide to feed the clips off the rods, said support having an abutting lip for engaging the 85 clips fed off the rods, and a clamp carried by the support for collapsing the clips at the lip, substantially as and for the purpose 90 set forth.
4. In combination with clips having eyelets at the ends thereof, a surgical instrument comprising an automatic clip feed presenting rods adapted to thread the eyelets of the clips, a support for the automatic 95 feed presenting an abutting lip against which the clips are fed, and a clamping tool for collapsing the clips at the lip, said support having a cut-out portion to allow a clip to bulge through the cut-out when collapsed 100 by the clamping tool.

GIULIO BACOLINI.
